DRAIN VALVE MECHANISM

James A. Campbell, Oakland, Calif., assignor to
The Westinghouse Air Brake Company, Wil-
merding, Pa., a corporation of Pennsylvania

Application July 2, 1942, Serial No. 449,527

8 Claims. (Cl. 303—88)

This invention relates to drain valve equipments, and more particularly to an automatic drain valve mechanism for effecting periodic discharge of water accumulating in the main reservoirs of a locomotive.

In the operation of railway locomotives in regions of high altitudes, or under cold weather conditions generally, one problem which has been encountered for many years without satisfactory solution has been the need for means to expel condensed moisture from the main reservoirs before the water can be carried to the feed valve and other devices of the air brake system, where freezing of such condensate would interfere with operation of the brakes. A number of automatic drain valve devices have been proposed for draining both the main reservoirs and the after-cooler sometimes associated therewith, some of which are rendered operative upon each application of the brakes, and others of which are designed for intermittent operation by the usual pump governors. Although a measure of success has been achieved with certain of these devices, there still exists a need for a dependable inexpensive automatic mechanism operable at regular intervals with a low consumption of main reservoir air to provide proper drainage of accumulated water from the system.

A principal object of my invention is to provide an improved drain valve mechanism fulfilling the above requirements.

Another object of the invention is to provide a drain valve mechanism which is operative periodically at predetermined intervals to eject condensate from a main reservoir or the like, regardless of the frequency of applications of the brakes, or of the functioning of the pump governor.

Other objects and advantages of invention will appear in the following more detailed description, taken in connection with the accompanying drawing, in which the single figure is a diagrammatic sectional view of a drain valve mechanism constructed in accordance with the invention.

For the purpose of disclosing the invention, the equipment shown in the drawing is represented in elementary form, and includes a main reservoir 1, which is adapted to be supplied with air under pressure by means of a suitable compressor, not shown, and which has associated therewith a pressure actuated drain valve device 2 and a timing valve device 3. It will be understood that in actual practice the drain valve device and timing valve device may be associated with more than one main reservoir, or with an after-cooler 55

or the like, depending upon the equipment carried by the locomotive.

The drain valve device 2 comprises a casing section 5 suitably secured to the bottom of the main reservoir 1, a casing section 6 bolted to the casing section 5, and a flexible diaphragm 7, which is clamped between the two casing sections in a canted position, forming on one side thereof a pressure chamber 8 and on the opposite side a chamber 9 communicating with a drainage tube 10. Formed in the casing section 5 is a condensate collection chamber 12 which communicates by way of a passage 13 with the interior of the main reservoir 1. A bore 14 connects the chamber 12 with a valve chamber 15, also formed in the casing section and communicating by way of a bore 16 with the ejection chamber 9. A double valve element 18 disposed within the valve chamber 16 is engageable with a seat 19 for controlling communication between the chambers 12 and 15, or alternatively with the valve seat 20 for controlling communication between chambers 15 and 9. The double valve element 18 is supported through the medium of a fluted stem 23 slidably fitting the bore 14, and a similar stem 24 slidably mounted in the other bore 16, it being noted that the valve element and stems are inclined in alignment with the axis of the canted diaphragm 7. The fluted stem 23 operatively engages a follower member 25 which is attached to the diaphragm 7, and which is subject to the force exerted by a coil spring 26 interposed between the follower element and an upper wall of the chamber 9. The spring 26 normally urges the diaphragm 7 downwardly and into engagement with a stop portion 27 of the casing. A coil spring 28 is interposed between the fluted stem 23 and an upper wall of the chamber 12 for urging the double valve element 18 downwardly into engagement with the seat 20, as shown in the drawing, in which position of the valve element communication is maintained between the chamber 15 and the chamber 12.

The timing valve device 3 comprises a timing reservoir 30 having a chamber 31 of predetermined volume, a casing section 32, which is bolted or otherwise secured to the reservoir, a casing section 33 similarly mounted on the casing section 32, and a strainer section 34 that may be mounted on the section 33. A suitable gasket, indicated at 35, may be interposed between the casing sections.

The strainer section 34 has a chamber 36 which communicates by way of a pipe 37 with a main reservoir 1, and contains suitably mounted

strainer material 37 for preventing passage of scale or other foreign matter through the device. The chamber 36 also communicates with a bore 39 formed in the casing section 33, and thence by way of a port 40 with a passageway 41, which extends through the casing section 32 and communicates with the timing chamber 31 and by way of a pipe 43 with the chamber 8 of the drain valve device 2. A choke element having a restricted passage 44 is interposed in the passageway 41 for controlling the rate of supply of air to the timing chamber 31.

Formed in the casing section 32 beneath the bore 39 is an enlarged bore 45, in which is slidably mounted a piston valve element 46 having a valve portion 47 that is normally maintained in engagement with a valve seat 48 for closing a port 50. The piston valve element 46 carries a stem 49, which extends upwardly through the bore 45 and into sliding engagement with the bore 39, the length of the stem being such as to maintain open the port 40 when the valve portion 47 is seated, as shown in the drawing. It will be noted that the diameter of the valve portion 47 is considerably greater than that of the stem 49. The piston valve element 46 is also provided with a restricted passage 51, forming communication between a chamber 52 at the lower face of the piston valve element and the portion of the bore 45 at the upper side thereof, which is connected to the atmosphere by way of a passage 53. It will be understood that the piston valve element 46 is thus designed for operation with a quick, or snap action, in response to an increase in fluid pressure initially forcing the valve portion 47 away from its seat and subsequently acting on the lower surface of the valve element exposed to the chamber 52, and that the element can be held in its uppermost position by a lower pressure than that required to unseat it.

In operation, compressed air supplied in the usual manner to the main reservoir 1 flows through the pipe 37, chamber 36, passage 39, port 40, and passageway 41 to the timing reservoir chamber 31, and also by way of pipe 43 to the chamber 8 in the main valve device 2. The pressure of air in the timing reservoir chamber 31 and the diaphragm chamber 8 is thus gradually increased at a rate determined by the size of the restricted passage 44 of the choke plug interposed in the passageway 41. When the pressure of air acting against the diaphragm 7 of the drain valve device has been thus increased sufficiently to overcome the opposing force exerted by the springs 26 and 28, the diaphragm is forced upwardly, thereby raising the double valve element 18 away from the lower valve seat 20 and into engagement with the upper valve seat 19. As the double valve element 18 thus traverses the distance between the two seats, the relatively high pressure of air contained in the main reservoir 1 acts against any accumulated water, which may have collected in the chamber 12 and connected chamber 15 by flow from the reservoir 1 through the passage 13, and quickly drives out such water by way of the chamber 9 and drainage tube 10. This discharge of compressed air from the main reservoir 1 is of course quickly terminated by engagement of the double valve element 18 with the upper seat 19, so that only a small amount of air is required for the operation. Drainage of water from the chamber 9 is facilitated by reason of the inclined position in which the diaphragm 7 is disposed.

Air under pressure is meanwhile continuously

supplied by way of passage 41 and the restricted passage 44 to timing chamber 31, and when the pressure effective on the surface of the valve portion 47 exposed to the passage 50 becomes great enough to overcome the weight of the piston valve element 46 and the opposing pressure of air acting on the stem 49, the element is forced upwardly. As the valve portion 47 is moved away from the seat 48, the pressure of air in the timing chamber becomes effective over the entire area of the valve element exposed to the chamber 52 whereupon the element is moved to its uppermost position with a snap action, the stem 49 being thereby operated to close the port 40. Further supply of air from the main reservoir to the timing chamber 31 is thus cut off, while air under pressure is discharged therefrom at a controlled rate by flow through the restricted passage 51 in the piston valve element 46 and thence through the atmospheric passage 53.

When the pressure of air in the timing chamber 31 and in the diaphragm chamber 8 connected thereto has been reduced sufficiently, the combined forces of the two coil springs 26 and 28 of the drain valve device are then rendered effective to shift the associated diaphragm 7, follower member 25 and double valve element 18 to the position in which they are illustrated in the drawing. In traversing the distance between the seat 19 and the seat 20, the double valve element 18 again effects a quick limited discharge of water that has been condensed from the air in the reservoir 1, as hereinbefore explained.

Continued flow of air under pressure from the timing chamber 31, passageway 41 and chamber 52 through the passages 51 and 53 finally results in reduction in the pressure acting upwardly on the piston valve element 46 to a value less than that required to hold the element in the uppermost position, whereupon that element is again moved to its seated position by the force of gravity and the air pressure acting on the stem 49. Communication between the passage 39 and port 40 is thereby reestablished, and the drain valve apparatus is conditioned for another cycle of operation as just explained.

It will be apparent from the foregoing description that an automatic drain valve and timing valve apparatus constructed in accordance with the invention may be mounted on a locomotive in any convenient position, with the timing valve device spaced any desired distance away from the drain valve device. It will further be evident that with the timing reservoir and associated elements properly proportioned with relation to the pressure carried in the main reservoir, the drain valve device will be rendered operative periodically and often enough to keep the reservoir substantially dry at all times.

Having now described my invention, what I claim as new and desire to secure by Letters Patent is:

1. In an automatic drainage apparatus for periodically discharging condensate from an air storage reservoir, in combination, a valve device operative to eject condensate from said reservoir in response to either an increase or a decrease in pressure of air in a chamber, a timing reservoir communicating with said chamber, means for supplying air under pressure to said timing reservoir, and valve means responsive to a predetermined increase in timing reservoir pressure to vent air from said chamber.

2. In an automatic drainage apparatus for periodically discharging condensate from an air

storage reservoir, in combination, a valve device operative to eject condensate from said reservoir in response to either an increase or a decrease in pressure of air in a chamber, a timing reservoir communicating with said chamber and with said storage reservoir, means restricting said communication between said timing and storage reservoirs, and valve means responsive to gradual increase in timing reservoir pressure to a predetermined value for venting air from said chamber and said timing reservoir.

3. In an equipment of the class described, the combination with an air storage reservoir of a fluid pressure actuated drain valve device operative to effect discharge of water condensed in said reservoir, and timing valve mechanism remote from said reservoir and drain valve device, said timing valve mechanism comprising valve means controlling the supply and release of air under pressure to and from said drain valve device, and timing means for causing operation of said valve means at predetermined intervals.

4. A timing valve apparatus for controlling periodic operation of a fluid pressure actuated drain valve for an air storage reservoir, comprising a timing reservoir, means providing communication through which air is supplied from the storage reservoir to said timing reservoir at a restricted rate, a snap acting valve element operative upon a predetermined increase in the pressure of air in said timing reservoir to vent air therefrom while cutting off said communication with the storage reservoir, said valve element being subsequently operative, when pressure of air in said timing reservoir has been reduced, for reestablishing communication thereto from said storage reservoir while stopping further venting of air, and means for communicating such variations in timing reservoir pressure to said drain valve device for effecting corresponding operation thereof.

5. A timing valve mechanism for controlling periodic operation of a fluid pressure actuated drain valve for an air storage reservoir, comprising a casing structure having a timing chamber, a communication formed in said casing structure through which air under pressure can be supplied from the storage reservoir to said timing chamber, air straining means and flow retarding means interposed in said communication, a reciprocating valve element slidably mounted in a bore in said casing for controlling communication from said timing reservoir to atmosphere, said valve element being constructed and arranged to control alternate increase and reduction in timing reservoir pressure, and means for communicating such periodic variations in pressure to said fluid pressure actuated drain valve device.

6. A timing valve mechanism for controlling periodic operation of a fluid pressure actuated

drain valve for an air storage reservoir, comprising a casing structure having a timing chamber, a communication formed in said casing structure through which air under pressure can be supplied from the storage reservoir to said timing chamber, air straining means and flow retarding means interposed in said communication, a reciprocating valve element slidably mounted in a bore in said casing for controlling alternate increase and reduction in timing reservoir pressure, said piston valve element having a vent valve portion always subject to timing reservoir pressure, an enlarged surface surrounding said valve portion and arranged to be subjected to timing reservoir pressure only when said valve portion is unseated, and a stem portion for controlling the communication between said storage and timing reservoirs, said stem portion having a pressure area less than that of said valve portion subject to storage reservoir pressure in opposition to the timing reservoir pressure acting on said valve element, and means for communicating such periodic variations to said fluid pressure actuated drain valve device.

7. In a drain valve equipment of the class described, the combination with a reservoir adapted to be supplied with air under pressure, of a drain valve device having a water accumulating chamber into which water can flow from said storage reservoir, a double valve in said chamber cooperable with either of two seats formed in said device, a movable abutment subject to variations in fluid pressure for moving said double valve from one seat to the other to effect periodic quick discharge of water from said accumulating chamber, and timing means operative by air under pressure from said storage reservoir for alternately increasing and reducing the fluid pressure acting on said movable abutment.

8. In a fluid pressure system including a receptacle for receiving fluid under pressure, in combination, a fluid pressure actuated drain valve device constructed and arranged to collect and effect discharge of water condensed in said receptacle, said drain valve device being operative periodically upon alternate variations in the pressure of fluid in a chamber within a predetermined range, and fluid pressure responsive timing valve means controlling the supply and release of fluid under pressure to and from said chamber, said timing valve means being automatically operative upon increase in pressure in said chamber to a maximum beyond said predetermined range for initiating gradual venting of fluid therefrom, and upon resultant decrease in said pressure to a minimum beyond said predetermined range for initiating gradual supply of fluid under pressure to said chamber.
